HEAT EXCHANGE DEVICE

Joseph B. Waller, Baltimore, Md.

Application September 6, 1946, Serial No. 695,137

8 Claims. (Cl. 62—129)

1

This invention relates to a heat exchange device and comprehends more particularly the regulation of temperature in the cooling chamber of a refrigerating unit or similar unit having a separate compartment for the coolant.

It is primarily the object of my invention to provide a cooling unit with novel means for conducting and regulating the exchange of heat between a cooled compartment and a coolant.

Another object of this invention is to provide a cooling unit of the above character provided with a manual control which sets the temperature desired and an automatic control which maintains the icebox substantially at that temperature.

Still another object of this invention is the provision of a portable refrigerating container of durable construction, having a separate Dry Ice or other coolant chamber contained therein and which has a channelized heat transfer system from the coolant chamber to the rest of the container in order that the internal temperature of the unit may be more readily controlled and maintained within desired limits, and at the same time the full efficiency of the coolant obtained.

With these and other objects in view, the invention broadly embraces incorporating with a refrigerating unit a novel heat exchange device which has both automatic and manual controls. The cooling effect is accomplished by heat being conducted from a contact surface in the cooling compartment through a heat conducting path to a surface in contact with a coolant, substantially all heat exchange taking place through said path. The heat contact surfaces are joined by a transverse conductive path which conducts heat from one of said surfaces to the other. Both manual and automatic means are provided for regulating the cross sectional area of the conductive path to thereby regulate the rate at which heat is exchanged from one contact surface to the other.

The above objects and other objects I accomplish by a combination and arrangement of parts of which I show a preferred embodiment in the accompanying drawings.

Referring to the drawings in which the same or similar reference numerals apply to identical parts:

Figure 1 is a top plan view, partly broken away, showing a portable refrigerating unit embodying the present invention.

Figure 2 is a side elevational view, partly in central transverse section, of the refrigerating unit shown in Figure 1.

2

Figure 3 is a vertical sectional view of the heat exchange device taken along the line 3—3 of Figure 2.

Figure 4 is a horizontal sectional view taken along the line 4—4 of Figure 2 in which the insulation has been omitted to clarify the disclosure.

Figure 5 is a transverse view taken along the line 5—5 of Figure 4.

Referring more particularly to the drawings, Figure 1 shows a portable refrigerating unit 1, with a cooling chamber 2, and compartment for a coolant 3. The unit is enclosed by insulation material 4 and the chamber 2 is thermally isolated from the compartment 3 by substantially heavy walls of insulation 5.

A heat transfer device, indicated generally as 6 and composed of a material having high heat conducting properties such as copper interconnects the compartment 3 and the chamber 2 through the insulating wall 5. This heat transfer device, as best seen in Figures 2 and 3 comprises a contact plate or surface 7 which occupies a horizontal position substantially covering the bottom of the compartment 3. A second plate or heat absorbing surface 8 is positioned in the chamber 2 and is connected with the plate 7 through the insulating wall 5 by means of a conducting element indicated generally as 9.

In accordance with the invention, the element 9 provides a heat conducting path of variable cross sectional area between the plates 7 and 8 and to accomplish this, the element 9 comprises a platelike member 10 which forms a continuous, permanent connection between the plates 7 and 8. As seen in Figure 3, one end 11 of the member 9 is attached, such as by screws to the plate 7. This edge is continuous across the upper end of member 9 and provides a substantial surface contact with the plate 7 while the opposite end of the member 9 is bifurcated, tapering to a pair of substantially narrow tips 12 which are connected such as by means of screws to the plate 8 and provide a surface contact of the member 9 therewith appreciably less than with the plate 7.

Rigidly attached to the plate 8 respectively adjacent each of the tips 12 but spaced therefrom are fixed strips 13 having diagonal free ends 14 while pivotally attached to the continuous portion 11 of the member 9 are a pair of movable strips 15 having diagonal free ends 16 adapted to make and break surface contact with the diagonal ends respectively of the strips 13. By means of this arrangement it will be seen that the mean cross sectional area of the heat conducting ele-

ment 9 and, as a consequence, the heat conducting capacity of the path formed thereby is increased or decreased as the strips 13 and 15 are in contact or parted. Moreover by virtue of the reduced cross sectional area of the permanent portion of the path afforded by the narrow tips 12, the degree of variability in heat conductivity and resulting heat transfer is increased.

To provide for automatic control of the heat conducting capacity of the connecting path between the plates 7 and 8 in order to maintain the temperature in the chamber 2 within desired limits of temperature range, the following mechanism is provided:

A round rod 17 journaled on the outer side wall of refrigerating unit 1 has knob 18 attached for manual rotation. This rod passes through the insulated wall of unit 1 and then through lower insulated portion of compartment 3 perpendicular to the plane of the conducting path 9. It terminates against a rotatable disc 19 journaled in a cup 20 positioned on an outer side wall of compartment 3 which is exposed to the atmosphere of chamber 2.

Concentric to the rod 17 is a square shaft 21 which extends almost the total length of the rod. Where shaft 21 crosses the plane of the conducting path 9 it is linked by means of a crank 22 to the middle of a cross bar 23 which is pivotally attached at each end 24 to the movable strips 15 which are thus moved, in parallel relation, to an equal extent with respect to fixed strips 13.

One end of shaft 21 extends into cup 20 on the outside of compartment 3 where it is secured to the free end of a bimetallic thermostat 25. This thermostat is fixedly clamped to disc 19 by means of clamps 26.

Temperature changes in chamber 2 cause only the free end of thermostat 25 to move, thus rotating shaft 21 and making and breaking contact between strips 13 and 15 through the linkage comprising crank 22 and cross bar 23. However, by manually turning knob 18, rod 17 will rotate disc 19 which in turn will move the thermostat 25 in toto and consequently actuate shaft 21 to make or break contact between strips 13 and 15. Thus the cooling action of the refrigerating unit can be changed at any given moment. In addition, the manual control obtained through knob 18 enables the setting of temperature range limits through which the thermostatic control is effected. Frictional engagement between the inside wall of cup 20 and the flat surface of disc 19 firmly holds the thermostat in the position as set by the knob 18, so that all movement of the bi-metallic strips is transmitted only through shaft 21. In other words, the manual setting may be such that either a great or a small temperature change is required to make contact between strips 13 and 15. But once the desired temperature range is reached the thermostat automatically holds the cooling chamber within that temperature range by alternately making and breaking contact between strips 13 and 15 to increase and decrease the cross sectional area of the conductive path, as the temperature in chamber 2 moves first to one limit and then to the other of the predetermined temperature range.

Mention should be made of the fact that plate 8 does not have to be a solid plate. It may be a foraminous plate or even a coil. By coil is meant not a fluid bearing coil but something in the nature of a coarse rod or a pipe which may have cooling fins on it.

It is apparent from the foregoing that the re-

frigerating unit works on a variable heat exchange principle of a new and improved character. The narrowing down of the permanent connections of the heat conducting path between the contact surfaces permits a definitely appreciable control of the temperature of the cooling compartment by action of the movable connections which make and break contact. As a result of manual setting, or a thermostatic setting co-operating with the manual setting, the cooling medium is thus efficiently used and not wasted by dissipation when not required. Furthermore, goods stored may be held substantially at desired temperatures.

While only one embodiment of the invention has been described, it is to be understood that such a heat exchange principle could readily be applied to large refrigeration units, refrigerating cars, cold storage rooms or even buildings, or any other refrigeration unit of whatever sort, nature, or description.

I claim:

1. In a heat exchange device, a cooling chamber, a compartment for containing a coolant, means forming a permanent metallic heat conducting path between said compartment and chamber, said means including at least one pair of separable metallic members adapted to contact each other to form a second heat conducting path between said compartment and said chamber, and means responsive to temperature changes of said chamber for making and breaking contact between said members.

2. In a heat exchange device, a cooling chamber, a compartment for containing a coolant, means including at least one pair of separable metallic members adapted to contact each other to form a heat conducting path between said compartment and chamber, one of said pair of members being fixed in position and the other member being movable, a thermostat within said chamber, means operatively connecting the thermostat to the movable metallic member for making and breaking contact between said fixed and movable members in response to temperature changes within said chamber, a manually controlled member to move the thermostat, and said movable member to set temperature limits within which the thermostat will be effective in making and breaking contact between the separable members.

3. In a heat exchange device, a cooling chamber, a compartment for containing a coolant, means including at least one pair of separable metallic members adapted to contact each other to form a heat conducting path between said compartment and chamber, one of each of said members being fixed in position and the other member being movable, a thermostat, a member connecting the thermostat to the said movable metallic member in order to make and break contact between said fixed and movable members in response to temperature changes within said chamber, a manually controlled member linked to the movable metallic member in order to make or break contact between the said separable members and thus change the cross sectional area of the heat conducting path.

4. In a heat exchange device, a cooling chamber, a compartment for containing a coolant, a contact surface in said chamber, a contact surface in said compartment, a permanent metallic heat conducting path between said contact surfaces making several times greater area contact with one of the surfaces than with the

other, at least one pair of separable members comprising fixed and movable metal strips adapted to contact each other to form an additional heat conducting path between said contact surfaces, a rotatable shaft, link means connecting the shaft to the movable strip for moving the same to make and break contact with the fixed strip, and thermostatic means for rotating the shaft.

5. In a heat exchange device, a cooling chamber, compartment for containing a coolant, a contact surface in said chamber, a contact surface in said compartment, a permanent metallic heat conducting path between said contact surfaces making several times greater area contact with one of the surfaces than with the other, at least one pair of separable members comprising fixed and movable metal strips adapted to contact each other to form an additional heat conducting path between said contact surfaces, a rotatable shaft linked to said movable metal strip and secured to the free end of a bimetallic thermostat, said thermostat being fixed on a surface which rotates through the action of a manual control.

6. In a heat exchange device, an insulated cooling chamber, an insulated compartment for containing a coolant, a contact surface placed horizontally in the bottom of said chamber, a contact surface in said compartment, a permanent metallic heat conducting path extending through the insulation between said surfaces making several times greater area contact with one of said surfaces than with the other, at least one pair of separable metallic members comprising fixed and movable metal strips adapted to contact each other to increase the cross sectional area of the heat conducting path, a rotatable shaft linked to said movable metal strip and secured to the free ends of a bimetallic thermostat, said thermostat being fixed to a

surface which rotates through the action of a manually controlled rod passing longitudinally through the center of the said rotatable shaft.

5. In a heat exchanging device, a cooling chamber, a compartment for a refrigerant, a heat conducting element in the cooling chamber for receiving heat from the chamber, a heat conducting element in the refrigerant compartment, a metallic sheet permanently connecting the elements, a second metallic sheet joining the elements, and means to disconnect the second metallic sheet responsive to the temperature in the chamber to control the rate of heat transfer between the elements.

10 15. In a heat exchanging device comprising a cooling chamber, a compartment for a refrigerant, a heat conducting plate in the chamber, a heat conducting plate in the compartment, a metallic sheet extending between the heat conducting plates to transfer heat from one of the plates to the other, said sheet having a large area in engagement with one of the plates and a small area in engagement with the other plate, metallic strips pivotally contacting the sheet adapted to move into and out of heat transfer relationship with the heat conducting plate having a small area of contact with the metallic sheet in response to temperature changes in the chamber.
